(57) **CLAIM**

The ornamental design for an enclosure for an electronic device, as shown and described.

DESCRIPTION

FIG. 1 is a perspective view of an enclosure for an electronic device, in which an aperture is located in at least a rear face of the enclosure, in accordance with one embodiment of the invention;

FIG. 2 is a front view of the enclosure of FIG. 1;

FIG. 3 is a rear view of the enclosure of FIG. 1;

FIG. 4 is a left view of the enclosure of FIG. 1;

FIG. 5 is a right view of the enclosure of FIG. 1;

FIG. 6 is a top view of the enclosure of FIG. 1; and

FIG. 7 is a bottom view of the enclosure of FIG. 1.

FIG. 8 is a perspective view of an enclosure for an electronic device, in which an aperture is located in at least a rear face of the enclosure, and extends through a side and through a front face of the enclosure, in accordance with one embodiment of the invention;

FIG. 9 is a front view of the enclosure of FIG. 8;

FIG. 10 is a rear view of the enclosure of FIG. 8;

FIG. 11 is a left view of the enclosure of FIG. 8;

FIG. 12 is a right view of the enclosure of FIG. 8;

FIG. 13 is a top view of the enclosure of FIG. 8; and,

FIG. 14 is a bottom view of the enclosure of FIG. 8.
